UNITED STATES PATENT OFFICE.

HORATIO OGDEN NELSON, OF LONG ISLAND CITY, NEW YORK.

DESIGN FOR A BICYCLE-COVER.

SPECIFICATION forming part of Design No. 26,487, dated January 5, 1897.

Application filed April 23, 1896. Serial No. 588,829. Term of patent 14 years.

To all whom it may concern:

Be it known that I, HORATIO OGDEN NELSON, a citizen of the United States, residing at Long Island City, in the county of Queens, in the State of New York, have invented and produced a new and original Design for Bicycle-Covers, of which the following is a specification, reference being had therein to the accompanying drawings.

Figure 1 is a side view of the covering, showing part of my design. Fig. 2 is a top view of my design.

The leading feature of my design comprises a sack or covering B, having upper and lower edges or boundary-walls parallel with each other, the upper wall being shorter than the lower and the two end walls being connected

with the extremities of the upper wall by lines departing at an angle thereto and curving at their other ends to meet the lower boundary-
walls of the cover. 20

b and *b'* represent a preferred form of fastenings for two of the edges of my cover.

What I claim, and desire to secure by Letters Patent, is—

The design for safety-bicycle covers substantially as herein shown and described.

In testimony whereof I affix my signature hereto, in presence of two witnesses, this 22d day of April, 1896.

H. OGDEN NELSON.

Witnesses:

H. V. N. PHILIP,
J. B. MAXWELL.
